COMBINED AIR DISTRIBUTION OUTLET AND LIGHTING FIXTURE

Walter W. Kennedy, Rockford, Ill., assignor to
Barber-Colman Company, Rockford, Ill., a cor-
poration of Illinois

Application May 17, 1948, Serial No. 146,414

Term of patent 14 years

(Cl. D48—23)

To all whom it may concern:

Be it known that I, Walter W. Kennedy, a citizen of the United States, residing at Rockford, in the county of Winnebago and State of Illinois, have invented a new, original, and ornamental Design for a Combined Air Distribution Outlet and Lighting Fixture, of which the following is a specification, reference being had to the accompanying drawings, forming a part thereof.

In the drawings:

Figure 1 is a perspective view of a combined air distribution outlet and lighting fixture showing my new design.

Fig. 2 is a cross section.

The dominant features of my design reside in

the portion shown by means of full lines in the accompanying drawings.

I claim:

The ornamental design for a combined air distribution outlet and lighting fixture, substan-
tially as shown and described.

WALTER W. KENNEDY.
